UNITED STATES PATENT OFFICE.

EDWARD WILLEY MARVEL, OF PHILADELPHIA, PENNSYLVANIA.

KEY-LOCK.

1,166,381.

Specification of Letters Patent. Patented Dec. 28, 1915.

Application filed March 6, 1913. Serial No. 752,305.

To all whom it may concern:

Be it known that I, EDWARD WILLEY MARVEL, a citizen of the United States, and resident of Philadelphia, in the State of Pennsylvania, have invented a certain new and useful Improvement in Key-Locks, whereof the following is a specification, reference being had to the accompanying drawings.

10 My invention relates to locks adapted for use in connection with safety deposit boxes and similar inclosures. It is the usual practice of lessors of such boxes to provide them with locks requiring two keys to operate them, to wit, a "guard" key, retained by the lessor, and a "main" key furnished to the lessee, and when there are two lessees the "main" keys furnished to the respective lessees of any given box are precisely alike.

15 Such an arrangement is objectionable because either lessee, in the absence of the other, may open the box.

Therefore, it is an object of my invention to provide a lock requiring three keys to operate it, to wit, a guard key, and two different main keys, the latter being respectively furnished to the two lessees; so that the presence or consent of both lessees is necessary to the opening of the lock.

30 As hereinafter described, my invention includes a lock having a rotary key hub with two separate keyways, respectively for a "guard" key and for the two "main" lessees' keys; a slide bolt arranged to be operated by rotation of said key hub; guard tumbler mechanism arranged to detain and release said bolt in accordance with the position thereof; main tumbler mechanism arranged to detain and release said bolt in accordance with the position thereof; and auxiliary tumbler mechanism operatively connected with the main tumbler mechanism; the arrangement being such that when said bolt is in locked position the guard tumbler mechanism prevents the operation of the main tumbler mechanism, so that the guard tumbler mechanism must be operated by the guard key, to permit the main tumblers to be operated, and some of the latter must be operated by the first lessee's key to set the auxiliary tumblers in position to permit the bolt to be shifted to unlocked position, by operation of the main tumblers, by the second lessee's key.

55 My invention includes the various novel features of construction and arrangement hereinafter more definitely specified.

In the drawings:—Figure I is an outer face view of a lock conveniently embodying my improvement. Fig. II is a plan view 60 of said lock. Fig. III is a view similar to Fig. I but with the casing front plate removed to show the lock mechanism in locked position, requiring three keys, to wit, a guard key and two main keys, to unlock it. 65 Fig. IV is a view similar to Fig. III but showing the lock mechanism as set, by the guard key, to permit its operation by said main keys. Fig. V is a view similar to Fig. IV but showing the lock mechanism as further set, by the first main key, with the auxiliary tumblers having their gatings in alinement, with their stump entered therein; said stump being carried by the detent lever of the guard mechanism. Fig. VI is a view 70 similar to Fig. V but showing the slide bolt withdrawn to unlocked position, by the second main key. Fig. VII is a view similar to Fig. III but with all of the tumblers omitted. Fig. VIII is a plan sectional view 80 of said lock, taken on the line VIII, VIII in Fig. I. Fig. IX is a vertical sectional view of said lock, taken on the line IX, IX in Figs. I, III and VIII. Fig. X is an elevation of the guard key. Fig. XI is an elevation of the first main or lessee's key. Fig. XII is an elevation of the second main, lessee's key.

In said drawings; 1 is the lock bolt which is fitted to slide in the lock casing 2 having 90 the cover 3 removably secured by the screws 4 in threaded engagement with the sockets 5 in said casing. Said bolt 1 slides on the stationary stud 6 which extends through the slot 7 in said bolt and limits the outward 95 locking movement thereof. Said bolt 1 carries the stump 10 fitted to enter the gatings 11 of the main tumblers 12 which are pivotally supported on said stud 6. Each of said tumblers 12 has a spring 14 bearing upon 100 said casing 2 and tending to thrust said tumblers downward to the position shown in Figs. III and IV with the key sweep edges 17 thereof bearing upon the rotary key hub 18 which is journaled in said casing 2 and 105 cover 3 as shown in Fig. VIII and provided with the cam 20 which turns in the recess 21 of said slide bolt 1 so as to shift the latter back and forth when said hub is turned. Said hub has two keyways 23 and 24 which 110 are conveniently formed in diametrical alinement and, when in registry with the respective slots 26 and 27 in the hub bearing 28 on said cover 3, said keyway 23 is adapt-

ed to receive the guard key 30 shown in Fig. X and said keyway 24 is adapted to receive main keys such as the keys 31 and 32 shown in Figs. XI and XII. Each of said tumblers 12 has a projection 35 adapted to be engaged by the hook end 36 of the detent 37 which is pivoted on the stationary stud 38 and has the spring 39 bearing at its free end upon the casing 2 and tending to turn said detent 37 into engagement with said projections 35 on said tumblers 12 so as to detain the latter in locked position as shown in Fig. III. Said detent 37 has the arm 41 extending in opposition to the arm 42 of the guard lever 44 so that when the latter, which is fulcrumed on the stationary stud 45, is rocked from the position shown in Fig. III to the position shown in Fig. IV, by the projection 46 on the cam 20 encountering the shoulder 47 on said lever 44, said detent hook 36 is released from the tumblers 12. Said guard lever 44 has the stump 50 adapted to enter the gatings 51 of the guard tumblers 53 which are pivoted on said stationary stud 38 and each provided with a spring 54 bearing at its free end upon said casing 2 and tending to turn said tumblers 53 into the position shown in Figs. III and VI, in which position they are stopped by their projections 56 encountering said stump 50. Said guard lever 44 has the arm 57 carrying the stud 58 which is adapted to be encountered by the releasing tumbler 59 which is pivoted on said stationary stud 38 and has the spring 60 bearing at its free end upon said casing 2 and tending to turn said tumbler into the position shown in Figs. III to VI inclusive. It may be observed that when said guard lever 44 is turned to the position shown in Figs. IV and V its stud 58 encounters said releasing tumbler 59 so that said guard lever 44 may be released and restored to its normal position, shown in Figs. III and VI, by downward movement of said releasing tumbler 59. Said main tumblers 12 have extensions 62 respectively adapted to encounter the pins 63 on the respective auxiliary tumblers 64 which are mounted to vertically reciprocate on the bearing lugs 65 and 66 of the fence 68 which, as best shown in Fig. VII, is pivotally connected with the slide bolt 1 by the screw 69 and has the spring 71 with its free end bearing against said casing 2, tending to turn said fence into the position shown in Fig. VII. Each of said auxiliary tumblers 64 has a gating 72 adapted to receive the stump 73 carried by the detent lever 37, as shown in Fig. V.

It may be observed that the free ends of the springs 14 of the main tumblers 12 bear upon the pins 63 of the auxiliary tumblers 64 and tend to thrust the latter downwardly to the position shown in Fig. III; and pressure of the stump 73 against said tumblers 64, when the detent 37 is rocked into released

position as shown in Fig. IV, swings said tumblers 64 to the left, from the position shown in Fig. III to the position shown in Fig. IV. Said guard key 30, first main key 31 and second main key 32, respectively shown in Figs. X, XI and XII, are used to manipulate said lock as follows:—The lock mechanism being in the position shown in Figs. I, II and III; the guard key 30 is inserted in the keyway 23 in the hub 18 and the latter turned, clockwise, approximately sixty degrees, the shape of said recess 21 in the slide bolt 1 being such as to permit corresponding movement of the cam 20 without shifting said bolt. Said key 30 is bitted so as to sweep the tumblers 53 into position to receive the stump 50 in their gatings 51 and to then turn said guard lever 44 into the position shown in Fig. IV, by the projection 46 on the cam 20 encountering said shoulder 47 on said lever. Thereupon, said hub 18 being returned to its normal position, shown in Figs. III and IV, and said key 30 being withdrawn, the lock is in condition to be operated by the first main or lessee's key 31 shown in Fig. XI. Said main key 31 being then inserted in the keyway 24 of the hub 18, the latter is turned, clockwise, from the position shown in Fig. IV to the position shown in Fig. V. Said key 31 is so bitted as to shift all of said main tumblers 12, and thereby raise all of the auxiliary tumblers 64 until their gatings 72 register with their stump 73, carried by the detent lever 37, whereupon, the spring 71 swings the fence 68 to the right, as shown in Fig. V, so that said gatings 72 receive the stump 73 as shown in said figure, thus setting the mechanism so that the slide bolt 1 may be shifted to unlocked position by the second main or lessee's key 32. Said key is so bitted as to shift all of said main tumblers 12 except the outer one, (which does not need to be shifted), to present their gatings 11 in alignment with the stump 10 on the bolt 1 so that the latter may be retracted. It is to be understood that as said main tumblers 12 are operated by the first main key 31 merely to raise the auxiliary tumblers 64, and are operated by the second main key 32 merely to present their gatings in registry with the stump 10; it is only necessary for said keys 31 and 32 to respectively operate such of the group of tumblers 12 as are necessary for the respective functions aforesaid. It may be observed that until the auxiliary tumblers are shifted by the first main key, as just described, retraction of the slide bolt 1 is prevented by the stump 73 on the detent lever 37 which is braced against the right hand edge of the auxiliary tumblers 64, by the guard lever 44; said auxiliary tumblers holding the slide bolt by engagement with the bearing lugs 65 and 66 of the element 68 which is pivotally secured to said slide bolt 1.

5 by the screw 69. Thereupon, said hub 18 being returned to its normal position, shown in Figs. III and IV, and said key 31 being withdrawn, the lock is in condition to be operated to retract said bolt 1 by the second main or lessee's key 32 shown in Fig. XII. Said main key 32 being then inserted in the keyway 24 of said hub 18 the latter is turned, clockwise, from the position shown in Fig. V to the unlocked position shown in Fig. VI. It may be observed that when the guard lever 44 is shifted from the normal unlocked position, shown in Fig. III, to the position shown in Fig. IV, by the operation 15 of the guard key above described, the projection 76 on said guard lever 44 encounters the lug 77 on the slide bolt 1; so that when the slide bolt is retracted to unlocked position, as above described, said guard lever 44 is returned to the normal position, as shown in Fig. VI, thus releasing the detent lever 37 and guard tumblers 53 so that they are also returned to the normal position, as shown in Fig. VI. Said slide bolt may be 20 returned to locked position by reversely rotating the key hub 18 by the key 32.

30 Although in the form of my invention herein described the first main or lessee's key 31 is so bitted as to shift all of the tumblers 12 except the outer one; it is to be understood that they may be otherwise bitted. Moreover, both groups of tumblers, 12 and 53, may be differently arranged in accordance with different bittings of keys 30, 31 and 35 32, and the permutability of the tumbler mechanism may be further increased by varying the key sweep edges of the respective tumblers.

40 It is to be understood that I do not desire to limit myself to the precise details of construction and arrangement herein set forth as it is obvious that various modifications may be made therein without departing 45 from the essential features of my invention as defined in the appended claims.

I claim:—

1. In a key lock, the combination with a slide bolt; of a rotary key hub with two 50 separate keyways, respectively for a guard key and for main keys; main tumbler mechanism arranged to detain and release said bolt in accordance with the position thereof; guard tumbler mechanism arranged to detain and release said bolt in accordance with the position thereof, including a guard lever and a detent for said main tumblers; releasing mechanism, including a releasing tumbler, and a lug on said slide bolt in cooperative relation with said guard lever, arranged to release said detent; a fence pivotally connected with said slide bolt; and auxiliary tumbler mechanism operatively connected with the main tumbler mechanism; whereby 55 when said bolt is in locked position the

guard tumbler mechanism prevents the operation of the main tumbler mechanism, so that the guard tumbler mechanism must be operated by the guard key, to permit the main tumblers to be operated, and some of 70 the latter must be operated by a main key to set the auxiliary tumblers to permit the bolt to be shifted to unlocked position, by operation of the main tumblers, by another main key.

2. In a key lock, the combination with a slide bolt; of a rotary key hub with two separate keyways, respectively for a guard key and for main keys; main tumbler mechanism arranged to detain and release 80 said bolt in accordance with the position thereof; guard tumbler mechanism arranged to detain and release said bolt in accordance with the position thereof, including a guard lever and a detent for said main tumblers; 85 releasing mechanism, including a lug on said slide bolt in cooperative relation with said guard lever, arranged to release said detent; a fence carried by said slide bolt; and auxiliary tumbler mechanism operatively connected with the main tumbler mechanism; 90 whereby, when said bolt is in locked position the guard tumbler mechanism prevents the operation of the main tumbler mechanism, so that the guard tumbler mechanism must be operated by the guard key, to permit the main tumblers to be operated, and some of 95 the latter must be operated by a main key to set the auxiliary tumblers to permit the bolt to be shifted to unlocked position, by operation of the main tumblers, by another main key.

3. In a key lock, the combination with a slide bolt; of a rotary key hub; main tumbler mechanism arranged to detain and release said bolt in accordance with the position thereof; guard tumbler mechanism arranged to detain and release said bolt in accordance with the position thereof, including a guard lever and a detent for said main tumblers; releasing mechanism, carried by 105 said slide bolt in cooperative relation with said guard lever, arranged to release said detent; a fence carried by said slide bolt; and auxiliary tumbler mechanism operatively 110 connected with the main tumbler mechanism; whereby, when said bolt is in locked position the guard tumbler mechanism prevents the operation of the main tumbler mechanism, so that the guard tumbler mechanism must be operated by the guard key, to permit the main tumblers to be operated, and some of the latter must be 115 operated by a main key to set the auxiliary tumblers to permit the bolt to be shifted to 120 unlocked position, by operation of the main tumblers, by another main key.

4. In a key lock, the combination with a slide bolt; of a rotary key hub; main tumbler mechanism arranged to detain and re- 130

lease said bolt in accordance with the position thereof; guard tumbler mechanism arranged to detain and release said bolt in accordance with position thereof; releasing mechanism, carried by said slide bolt, arranged to release said guard mechanism; a fence carried by said slide bolt; an auxiliary tumbler mechanism operatively connected with the main tumbler mechanism; whereby, 10 when said bolt is in locked position the guard tumbler mechanism prevents the operation of the main tumbler mechanism, so that the guard tumbler mechanism must be operated by the guard key, to permit the 15 main tumblers to be operated, and some of the latter must be operated by a main key to set the auxiliary tumblers to permit the bolt to be shifted to unlocked position, by operation of the main tumblers, by another 20 main key.

5. In a key lock, the combination with a slide bolt; of main tumbler mechanism arranged to detain and release said bolt in accordance with the position thereof; guard tumbler mechanism arranged to detain and release said bolt in accordance with the position thereof; an element pivotally connected with said slide bolt; and auxiliary tumbler mechanism carried by said element 25 and operatively connected with the main tumbler mechanism; whereby, when said bolt is in locked position the guard tumbler mechanism prevents the operation of the main tumbler mechanism, so that the guard 30 tumbler mechanism must be operated by the guard key, to permit the main tumblers to be operated, and some of the latter must be operated by a main key to set the auxiliary tumblers to permit the bolt to be shifted to 35 unlocked position, by operation of the main tumblers, by another main key.

6. In a key lock, the combination with a slide bolt; of main tumbler mechanism arranged to detain and release said bolt in accordance with the position thereof; guard tumbler mechanism arranged to detain and release said bolt in accordance with the position thereof; and auxiliary tumbler mechanism operatively connected with the main 45 tumbler mechanism; whereby, when said bolt is in locked position the guard tumbler mechanism prevents the operation of the main tumbler mechanism, so that the guard tumbler mechanism must be operated by the 50 guard key, to permit the main tumblers to be operated, and some of the latter must be operated by a main key to set the auxiliary tumblers to permit the bolt to be shifted to unlocked position, by operation of the main 55 tumblers, by another main key.

7. In a lock, the combination with a slide

bolt; of main tumbler mechanism arranged to detain and release said bolt in accordance with the position thereof; an element pivotally connected with said slide bolt, and auxiliary tumbler mechanism, carried by said element and arranged to be operated by the main tumbler mechanism. 65

8. In a lock, the combination with a slide bolt; of main tumbler mechanism arranged to detain and release said bolt in accordance with the position thereof; guard tumbler mechanism arranged to detain and release said bolt in accordance with the position thereof; and auxiliary tumbler mechanism 75 arranged to be operated by the main tumbler mechanism.

9. In a lock, the combination with a slide bolt; of main tumbler mechanism arranged to detain and release said bolt in accordance with the position thereof; a fence pivotally connected with said slide bolt; an auxiliary tumbler carried by said fence; and means operatively connecting said main tumbler mechanism with said auxiliary tumbler 80 mechanism, whereby the latter is controlled 85 by a key.

10. In a lock, the combination with a slide bolt; of main tumbler mechanism arranged to detain and release said bolt in accordance with the position thereof; guard tumbler mechanism arranged to detain and release said bolt in accordance with the position thereof; and auxiliary tumbler mechanism pivotally connected with said slide bolt and 90 operatively connected with the main tumbler mechanism whereby, when said bolt is in locked position the guard tumbler mechanism prevents the operation of the main tumbler mechanism, so that the guard tumbler mechanism must be operated by the 95 guard key, to permit the main tumblers to be operated, and some of the latter must be operated by a main key to set the auxiliary tumblers to permit the bolt to be shifted to 100 unlocked position, by operation of the main tumblers, by another main key.

11. In a lock, the combination with a slide bolt; of main tumbler mechanism arranged to detain and release said bolt in accordance with the position thereof; an auxiliary tumbler mechanism pivotally connected with said bolt and arranged to be operated by the main tumbler mechanism. 110

In testimony whereof, I have hereunto signed my name at Philadelphia, Pennsylvania, this 27th day of February, 1913.

EDWARD WILLEY MARVEL.
